UNITED STATES PATENT OFFICE.

LOUISE M. SPECHT, OF CHICAGO, ILLINOIS, ASSIGNEE OF ONE-HALF TO JOHN A. SHIMMER, OF CHICAGO, ILLINOIS.

RADIATOR AND ELECTRIC HEATING FIREPLACE.

Application filed April 18, 1919. Serial No. 299,974.

To all whom it may concern:

Be it known that I, Louise M. Specht, a citizen of the United States, residing at Chicago, in the county of Cook and State of Illinois, have invented certain new and useful improvements in Radiator and Electric Heating Fireplaces; and I do hereby declare the following to be a full, clear, and exact description of the invention, such as will enable others skilled in the art to which it appertains to make and use the same.

This invention relates to heating systems and the primary object of the invention is to provide an improved fireplace construction embodying an electric heater and a radiator, which can be used independently or together to form the heating means.

Another object of the invention is to provide an improved fireplace construction embodying an electric heater arranged on the grate thereof, which includes a plurality of resistance coils, all or any number of which can be brought into operation and a steam or hot water radiator arranged in rear of the grate and hidden from the view of the observer.

Another object of the invention is to provide improved means for locking the controlling switch of the electric heater against movement, when the circuit is closed, so as to make it necessary to open the circuit to move the lever and thus eliminate sparking of the lever when the same is moved over the contact points.

A further object of the invention is to provide an improved fireplace having a steam or hot water radiator concealed in the rear thereof and having means for allowing a circulation of air around the radiator, whereby the room in which the fireplace is positioned will be heated.

A still further object of the invention is to provide an improved ornamental fireplace of the above character, which is durable and efficient in operation, one that is simple and easy to manufacture, and one that can be placed upon the market at a reasonable cost.

With these and other objects in view, the invention consists in the novel construction, arrangement and formation of parts, as will be hereinafter more specifically described, claimed and illustrated in the accompanying drawings, forming a part thereof, in which:

Figure 1 is a front elevation of the improved fireplace.

Figure 2 is a side elevation of the same.

Figure 3 is a vertical section taken on the line 3-3 of Figure 1.

Figure 4 is a detail section through the device taken at right angles to Figure 3.

Figure 5 is a detail vertical section through the illuminating means for the electric heater.

Figure 6 is a vertical section through the electric heater, showing the circuit diagrammatically.

Figure 7 is a detail section through the switch for controlling the flow of current through the electric heating resistance coils.

Referring to the drawings, in detail, where-

in similar reference characters designate corresponding parts, throughout the several views, the numeral 1 generally indicates the improved device, which is preferably formed of metal or the like and includes the mantel-

piece 2, the front wall 3, which is suitably ornamented, as shown in Figure 1, to present a pleasing appearance and the side walls 4. The front wall 3 is provided with an inwardly extending section 5 which is adapted

to receive the grate 6. The extension 5 includes the upper downwardly and rearwardly inclined wall 7 the lower wall 8, side walls

9, and the rear wall 10, which extends the entire length and height of the device. The

lower wall 8 forms the bottom of the grate 6 and projects outwardly and beyond the front wall 3 and has secured thereto the upwardly extending bars 11 forming the front wall of the grate. The bottom wall 8 in-

cludes the downwardly extending flange 12, which rests upon the shoulder formed upon the front wall directly below the bars 11 and this portion is provided with a suitable longitudinally extending opening in which

is fitted a metal grill 13, for a purpose which will hereinafter more fully appear. The front wall 3 around the extension 5 is formed from suitable reticulated material

14 so as to allow the circulation of air therethrough. The reticulated material can be suitably ornamented, as shown in Figure

1, if desired.

An electric heater 15 is positioned on the grate 6 and includes a plurality of resistance coils 16 inserted in plaster of Paris or the like which is formed and suitably colored to represent coals or the like. The plaster of Paris may be provided with any number of suitable apertures 17 so as to allow the pas-

sage of air therethrough. A nipple 18 having its upper end provided with an outwardly extending flange 19 is embedded in the plaster of Paris and extends downwardly 5 therefrom and through an aperture 20 in the lower wall 8 and this nipple receives the electric wiring for the heater.

One terminal of the coils 16 is connected by a wire 22 to one of the line wires 23, 10 which has its opposite end connected to one terminal of a suitable battery or other electrical source 24'. The other line wire 22' extends from the opposite terminal of the electric battery 24' and is connected to one 15 end of a switch 21 of the push button type and a wire 23' is connected to the push switch 21 and a switch lever 24, which is pivotally connected at one end thereof by means of a suitable pivot pin 40 to the upper 20 wall of the substantially rectangular casing 41. This lever is adapted to have its free end contact with any one of the contact points 25, which have wires 26 connected thereto which extend to different portions 25 of the coils 15. This arrangement permits any variation in the heat desired, as any portion or all of the coils may be brought into operation by suitable manipulation of the switch lever. The free end 30 of the switch lever 24 has an upstanding handle 42 by means of which the lever is readily manipulated. The end of the lever directly below the handle 42 is provided with a substantially convex contact member 43 which is adapted to engage any one of the contact points 25, which has the upper surface thereof convex as at 44 to receive the concaved portion of the lever. This forms positive means for forming a contact 40 between the lever and the points. The rear end of the lever 24 is enlarged and rounded and is provided with a plurality of inwardly extending radial notches 45 which correspond to the points 25 of the resistance coils 16 and a locking lever 46 is adapted to engage in any one of the notches and to hold the lever against movement. The lever 46 is pivoted intermediate its ends on a suitable pin 47 in the casing 45 and has the rear end thereof bent upwardly, as at 48, which is extended through a suitable aperture 49 in the upper wall of the casing, so as to engage in the notches 45. The opposite end of the lever 46 carries 55 the armature 50, which is disposed directly over the coil 51; so that when the current passes through the coil, the same will attract the armature and thus force the end 48 of the lever upward into engagement 60 with one of the notches. When the circuit is opened, the upturned end 46 is thrown out of engagement with the notches by means of the coil spring 52, which has its ends bearing respectively against the upper 65 per wall of the casing and the upper surface

of the rear end of the lever 46. One terminal of the coil 51 is connected by means of a branch wire 53 to the wire 23', and the opposite terminal of the coil is connected by means of the wire 54 to the line wire 23, and thus when the circuit is closed by means of the push switch 21, a portion of the current will flow through the coil and thus attract the armature and prevent movement of the lever 24. 75

A radiator 28 of the usual or any preferred construction, used for steam or hot water heat, is arranged in rear of the wall 10 which has openings 29 formed adjacent to the bottom edge thereof, which is in direct alignment with the grill 13, so as to permit cold air to readily enter behind the wall at the bottom of the radiator. The wall 10 adjacent the upper edge thereof is provided with openings 30, through which warm air is adapted to circulate. The air is then allowed to enter the room through the reticulated portion 14 in the front wall 2. A rear plate 31 is carried by the rear wall 10 in spaced relation thereto and this plate has the upper and lower ends thereof curved forwardly into engagement with the front wall and secured thereto by any suitable means. The curvature of the upper and lower ends of the plate 31 forms means for deflecting the air so as to form a suitable circulation around the radiator. 85

A relatively small casing 33 is arranged directly in rear of the electric heater 15 and the front wall of the same is provided with a covering of asbestos or other non-conducting heat material 34, so as to protect the casing from the heat generated by the electric heater. An incandescent lamp 35 is arranged in the casing and connected to suitable electric wires 35', which have a snap switch 36 interposed between the same so as to cut off the incandescent lamp when so desired. The upper wall of the casing 33 is formed from red glass or the like, so that when the incandescent lamp is lit, the red light emitted from the casing will give the effect as if the heater 15 was burning. The switches 21, 24 and 36 are located adjacent to one end wall of the device, which is provided with a suitable hinged door 38, so that the same may be readily reached to control the electric heater and the incandescent lamp. The valve of the radiator is also located adjacent to this door, so that the heat of the radiator may be readily turned off or on. 110

From the foregoing description, it can be seen that an improved fireplace is provided, of exceedingly ornamental appearance, 125 in which an electric heater and a radiator are arranged so that either one or both can be used when so desired.

In practice, I have found that the form of my invention illustrated in the accompany- 130

ing drawings and referred to in the above description, as the preferred embodiment, is the most efficient and practical; yet realizing the conditions concurrent with the 5 adoption of my device will necessarily vary, I desire to emphasize that various minor changes in details of construction, proportion and arrangement of parts may be resorted to, when required without sacrificing 10 any of the advantages of my invention as set forth.

What I claim as new is:

1. A heating means comprising a wall, a wall spaced from said wall intermediate its 15 ends, a heater intermediate said walls, one of said walls having openings adjacent opposite ends of the heater for circulation of air about the heater and the other wall at its ends being deflected toward and relatively to said openings.

2. A heating means comprising a wall, a wall spaced from said wall intermediate its ends, a heater intermediate said walls, one of said walls having openings adjacent opposite ends of the heater for circulation of air about the heater and the other wall at its ends being deflected toward and relatively to said openings, and means extending outwardly from one of said walls to provide 30 a grate.

3. A heating means comprising a wall, a wall spaced from said wall intermediate its ends, a heater intermediate said walls, one of said walls having openings adjacent opposite ends of the heater for circulation of air about the heater and the other wall at its ends being deflected toward and relatively to said openings, and means extending outwardly from one of said walls of the lower- 35

most openings to provide a grate, and a supporting means for the grate at the outer portion of the grate having means there-through for entrance of air.

4. A heating means comprising a wall, a wall spaced from said wall intermediate its 45 ends, a heater intermediate said walls, one of said walls having openings adjacent opposite ends of the heater for circulation of air about the heater and the other wall at its ends being deflected toward and relatively to said openings, and a hollow body extending from the same wall as and above the grate in communication with the uppermost openings, and means for escape of heated air from said body. 55

5. A heating means comprising a wall, a wall spaced from said wall intermediate its ends, a heater intermediate said walls, one of said walls having openings adjacent opposite ends of the heater for circulation of 60 air about the heater and the other wall at its ends being deflected toward and relatively to said openings, means extending outwardly from one of said walls of the lowermost openings to provide a grate, a supporting means for the grate at the outer portion of the grate having means there-through for entrance of air, and a hollow body extending from the said walls as and above the grate in communication with the uppermost openings, and means for escape of heated air from said body. 65

In testimony whereof I affix my signature in presence of two witnesses.

LOUISE M. SPECHT.
